STEAM GENERATING SYSTEM

John J. Saunders and Pierre Fugueme,
Edmonton, Alberta, Canada

Application July 18, 1933, Serial No. 681,044

1 Claim. (Cl. 137—101)

This invention relates in general to steam generating systems, and more particularly has reference to a device for the generation of steam and means for supplying water thereto.

5 In the past it has been customary to provide boilers for the generation of steam, such boilers being of considerable size and holding various quantities of water for transformation into steam.

10 It is an object of this invention to provide a means for the generation of steam wherein only a very small amount of water is required to be heated to begin the generation of steam, and yet wherein the water supply is constantly replenished at any desired rate by a positively acting 15 means for maintaining the water level and preventing it from becoming either too high or too low.

20 Means have been previously devised for generating steam, in which it was required to heat only a small amount of water before steam could be produced, but such means has been incapable of producing any considerable quantity of steam because of the fact that it has been impossible to maintain exactly the proper water supply where 25 so small a quantity of water has been involved. It is therefore an object of this invention to provide such a device in which the quantity of water necessary to be heated will be small, yet in which the quantity of water involved in maintaining the 30 proper water level is sufficiently large to enable this level to be maintained. It is a further object to provide a means for admitting such water, which means will be normally closed by the pressure from the water supply, but which will be 35 positively opened when the water falls below a predetermined level.

35 Referring now more particularly to the accompanying drawing in which like numerals indicate corresponding parts throughout, the single figure 40 is a diagrammatic illustration partly in section illustrating the invention.

45 In accordance with this invention, the steam generator consists of a plurality of generating tubes 1 connected at their upper ends to a steam header 2, which is in turn in communication with a steam main 3 utilized for the purpose of conveying steam to the point at which it is to be used.

50 The tubes 1 are of comparatively low capacity, and are adapted to have a water level maintained therein at some predetermined position such as indicated by the dotted line 4. Water is supplied to these tubes through a pipe 5 communicating with their lower ends, a drop 6 being formed in

the intake pipe for the purpose of retarding back-flow.

5 The pipe 5 is connected at 7 to a T-coupling 8, one branch 9 of which is provided with a pipe 10 communicating at 11 with the lower portion of a reservoir 12. The other branch 13 of the T-coupling 8 is adapted to receive a nipple connection 14 to which is secured at 15 a second T-coupling 16. One branch 17 of the T-coupling 16 receives one end of a second nipple connection 18, 10 the other end being received by the branch 19 of a T-coupling 20. The T-coupling 20 is secured to the extension 21 of the bottom of the reservoir 12, and is adapted to receive one end of the large 15 nipple 22. The lower end of this nipple is provided with a beveled seat 23 for a purpose to be later described and is received within a valve chamber 24. The valve chamber 24 is provided with a theraded lower portion 25 adapted to receive a plug 26 having a squared end 27 thereon for the purpose of receiving a wrench. Likewise, the valve chamber 24 is provided with a connection 28 into which is threaded one end of a supply pipe 29 for the purpose of supplying 20 water under pressure to the reservoir 12. 25

25 The reservoir is connected adjacent its upper end by means of a pipe 30 to a T-coupling 31 which in turn communicates with the steam main 3 and the header 2 through the pipe 32. The T-coupling 31 is connected with the T-coupling 16 30 by means of a pair of nipples 33 and 34 respectively, a pipe 35 and a pair of couplings 36 adapted to receive the ends of a glass water level indicator 37. The indicator 37 is securely connected to the couplings 36 by means of packing 35 nuts 38. Each of the couplings 36 is provided with a valve 39 having a handle 40 for the purpose of shutting off communication to the glass water level indicator 37 when so desired.

40 The reservoir 12 is provided with a removable cover 41 secured in place by means of bolts 42 and nuts 43 passing through the marginal portion of the cover 41 and an outwardly turned flange 44 extending from the upper edge of the reservoir. The wall of the reservoir is likewise provided with a pair of bearing portions 45 projecting outwardly therefrom and threaded to receive a cap 46 and a packing nut 47 respectively. 45

45 Journalized within the bearings 45 is a shaft 48 having an offset crank portion 49 substantially 50 at the center of the reservoir 12. To this crank portion 49 is secured a rod 50 by means of a cap member 51 and bolts or the like 52. The rod 50 is provided with a collar or enlarged portion 53 against which the bottom of a bucket-like recep- 55

tacle 54 is adapted to rest. The rod 50 extends through the hole 55 in the bottom of this receptacle and the receptacle is firmly secured in place by means of the nut 56. The portion 57 of the 5 rod 50, which portion extends below the receptacle 54 and into the valve chamber 24, carries at its end a valve 58 adapted to seat against the valve seat 23 and be held thereagainst by counterweight 61.

- 10 The shaft 48 extends out through the packing nut 47 and is provided at its end with a crank pin 59 to which is secured a rod 60 carrying a weight 61 secured thereto by means of the set screw 62. This weight 61 is so arranged as to form a partial counterbalance for the receptacle 54 and 15 tend to urge it upwardly so as to seat the valve 58 against the seat 23.

In the structure just set forth, which is adapted to be used for supplying high pressure steam, 20 it is necessary to supply feed water to the reservoir at a higher pressure than carried in generator so as to overcome the pressure of the steam. When water is admitted to the reservoir, it is allowed to flow in until it fills the reservoir 25 to a predetermined point and overflows into the receptacle 54 thus filling the receptacle. The weight 61 is sufficient to counterbalance the weight of the receptacle under these conditions and cause the receptacle to float even though it 30 is full of water, thus allowing the pressure of water within the supply pipe 29 to close the valve 58 and maintain it positively in closed position. However, when the water level in the reservoir falls below a predetermined point, the water does 35 not run out of the receptacle 54, but instead serves to give this receptacle sufficient weight to open the valve 58 against the high water pressure in the supply pipe. The presence of the reservoir 12 separate and apart from the tubes 1 40 increases the size of the body of water and enables the proper maintenance of the water level within the tubes 1, it being readily apparent that as soon as the water within the tubes is converted

into steam, a new supply will be introduced from the reservoir 12. The water level in the tubes can thereby be more evenly maintained because of the presence of the reservoir 12 than it could be if only the water within the tubes were to be 5 considered.

It will be seen from the above that a device has been provided for carrying out all of the objects of this invention in a satisfactory and efficient manner. It is apparent, however, that various 10 changes may be made in the details of construction and arrangement of parts without departing from the spirit or scope of this invention as set forth in the appended claim.

What we claim is:—

15 A water regulator for a steam generator, said regulator comprising a reservoir, means connecting the upper part of said reservoir with the steam space in the generator, means extending directly downwardly from the bottom of said reservoir for supplying water to the reservoir, a valve within said downwardly extending means for closing the same, a bucket within said reservoir, a rod extending down through said downwardly extending means and connecting said bucket and said valve, said rod having a locked connection with the base of the bucket and having its upper end upstanding through and above the bucket, a rotatable shaft extending through the wall of said reservoir and having a crank 20 within the reservoir engaging the upper end of said rod to raise or lower said bucket, a counterweight externally of said reservoir in connection with said shaft and normally tending to rotate the shaft in a direction to raise said bucket and 25 move said valve to closed position, lateral means connecting said downwardly extending means at a point above said valve with the water space in said generator, and means connecting the bottom of said reservoir with said lateral means in- 30 35 intermediate its ends.
